UNITED STATES PATENT OFFICE

112,685

DESIGN FOR A WEIGHING SCALE

William Watling, Chicago, Ill.

Application October 5, 1938, Serial No. 80,274

Term of patent 14 years

To all whom it may concern:

Be it known that I, William Watling, a citizen of the United States, residing at Chicago, in the county of Cook and State of Illinois, have invented a new, original, and ornamental Design for Weighing Scales, of which the following is a specification, reference being had to the accompanying drawing, forming part thereof, in which

Fig. 1 is a front elevation of a weighing scale embodying my design;

Fig. 2 is a side view of the scale as seen from the right in Fig. 1; and

Fig. 3 is a top plan view of my weighing scale.

I claim:

The ornamental design for a weighing scale, as shown.

WILLIAM WATLING.
